UNITED STATES PATENT OFFICE.

KNOWLSON TOWNSEND, OF SAN FRANCISCO, CALIFORNIA.

STEAM-BOILER-TUBE RETARDER.

1,174,538.

Specification of Letters Patent.

Patented Mar. 7, 1916.

Application filed August 21, 1915. Serial No. 46,637.

To all whom it may concern:

Be it known that I, KNOWLSON TOWNSEND, residing at San Francisco, in the county of San Francisco and State of California, have invented a new and Improved Steam-Boiler-Tube Retarder, of which the following is a specification.

This invention relates to that class of devices used in connection with the flues or smoke tubes of boilers and particularly to that form of devices adapted for being introduced into the said flue tubes for retarding or slowing the progress of the combustion gases through the tube in such a manner as to cause the said gases to develop their heat units in passing through and contacting with the tube walls more than is the case where retarders are not used.

The object of my invention is to provide a retarding means of the general character stated, which, when in operative connection with the tube can be readily adjusted for reducing the area of the tube, from the maximum down to one-half, more or less, for slowing the combustion gases as they pass through the tube, to thereby obtain the greater absorption of the heat units due to the increased time contact of the hot gases with the walls of the tube.

Another and essential object of my invention is to provide a retarding means or device as stated, of a very simple and inexpensive construction and so designed that when inserted in the tube it may be readily adjusted for reducing the flue area, as desired, without renewing or removing it from the tube.

Further my invention provides for making my improved form of retarder out of the conventional form of retarders, preferably the common twisted retarder, now in general use.

With other objects in view, all of which will be hereinafter fully explained, my improved boiler tube retarder embodies the peculiar features of construction and novel combination of parts, all of which will be hereinafter fully explained, specifically pointed out in the appended claims, and illustrated in the accompanying drawing, in which:

Figure 1 is a longitudinal section of a portion of a single flue tube with my retarder in place, the same being shown as adjusted all the way in the tube for cutting the area of the tube into one-half. Fig. 2

is a similar view that shows the retarder as projected out beyond the tube outlet for cutting down less than one-half of the tube area. Figs. 3 and 4 are end views of the 60 retarder and the tube, arrangement shown in Figs. 1 and 2. Fig. 5 is a longitudinal section of a tube with a slightly modified form of my retarder operatively connected therewith. Fig. 6 is a similar view of a 65 further modification hereinafter referred to. Fig. 7 is a detail view of one end of the ordinary twisted retarder, showing the manner in which the retarding prongs are formed thereon. Fig. 8 is a diagrammatic, 70 longitudinal section of a steam boiler with my improved construction of retarders applied for use. My improved boiler tube retarder is adapted for either marine or stationary engines, but mostly for use in boilers using oil for fuel. 75

In carrying out my invention, I shape up the retarder, preferably by taking the common type of twisted retarder as used now, and form, by sawing or otherwise, two 80 cuts 2 in one end 1 thereof, parallel with each other and equally spaced apart.

When the retarder is intended for cutting down the flue area to the maximum amount, say one-half of the normal area, the said retarder is inserted into the outlet end of the tube 3, up to the point where the cuts 2 begin, and after it is thus positioned the three prongs 4^a, 4—4 formed by cutting the end of the retarder as stated, are bent back at 90 right angles to the body of the retarder, the central prong 4^a, being bent up and the other two prongs 4—4 bent down flatwise against the tube beading, as is clearly shown in Figs. 1 and 3, it being understood that when the 95 prongs are thus formed the retarder can be extended into the tube to the limit and thereby reduce the area of the tubed flue to the greatest extent, such reduction of tube area thereby greatly retarding the hot gases 100 and creating, as it were, more complete combustion of the gases as they pass through the tube.

By reason of forming the outer end of the retarder with long prongs of uniform 105 widths, and of bendable material as shown, the said prong portions can be again bent between their ends to form prong fingers 5, the said fingers being bent inwardly so as to come up against the tube sheet 6 as is 110 shown in Fig. 2, it being understood that the greater the length of the said fingers 5, the

farther out from the tube outlet the retarder is projected, and hence the area is increased above one-half in accordance to the position of the said outer end of the retarder.

5 If, at any time, it is desired to reduce the tube area more than one-half, the retarder may be formed, by punching or otherwise, with one or more supplemental prongs 8 as shown in Fig. 6, but such supplemental 10 prongs are not essential since to reduce the area of the tube to one-half would be enough.

If the retarders, when short, have a tendency to work out of the tube, they can be made with swaged portions 9, formed by 15 striking the retarder at its opposite edges with the peen of a hammer to provide for holding the retarder in a tight frictional contact with the flue as is clearly shown in Fig. 5.

20 From the foregoing description taken in connection with the drawings the complete arrangement, the manner of using, and the advantages of my improved retarder will be readily apparent to those skilled in the art 25 to which my invention relates.

What I claim is:

1. In a boiler, the combination of a flue tube and a retarder, the said retarder comprising a metal strip insertible into the flue

30 to divide the flue into a pair of air passages

the outer end of the strip having bendable portions adapted for being bent over the tube outlet to restrict the area of the said outlet.

2. In a boiler, the combination of a flue 35 tube and retarder, the said retarder comprising a metal strip insertible into the flue, the outer end of the said strip having a central prong like portion bent in one direction at right angles to the strip and another pair of 40 prongs, one at each side of the central prong and bent in the opposite direction, the said bent prongs forming closure means for partly shutting off the flue outlet.

3. In a boiler, the combination of a flue 45 tube and retarder, the said retarder comprising a metal strip insertible into the flue, the outer end of the said strip having a central prong like portion bent in one direction at right angles to the strip and a pair of 50 prongs, one at each side of the central prong and bent in the opposite direction, the said bent prongs forming closure means for partly shutting off the flue outlet, the said prongs having end members bent inwardly 55 at right angles to the body of the prongs to produce abutting members adapted for resting against the flue sheet of the boiler when the retarder is pushed home into the flue.

KNOWLSON TOWNSEND.
